UNITED STATES PATENT OFFICE.

ARTHUR L. SMYLY, OF CHICAGO, ILLINOIS.

FLUID-PRESSURE GOVERNOR.

1,293,227.

Specification of Letters Patent.

Patented Feb. 4, 1919.

Application filed May 27, 1916. Serial No. 100,193.

To all whom it may concern:

Be it known that I, ARTHUR L. SMYLY, a citizen of the United States of America, and resident of Chicago, Cook county, Illinois, have invented a certain new and useful Improvement in Fluid-Pressure Governors, of which the following is a specification.

My invention relates to fluid-pressure governors in general, but more particularly to those employed for controlling the supply of illuminating or fuel gas, and especially to those which have an inlet-valve which is automatically controlled by a diaphragm, or other suitable means.

Objects of my invention are to provide an improved construction and arrangement whereby the movable valve-element is more easily adjusted and more readily removed from the governor than heretofore; to provide an improved construction and arrangement whereby the lever-arm which connects the valve-mechanism with the diaphragm can be lifted out of its bearings and moved endwise out of the way in order to afford access to the valve-seat; to provide an improved construction and arrangement whereby it will not be necessary to remove the entire cover of the governor-casing when it is desired to obtain access to the valve-mechanism; to provide an improved construction and arrangement whereby short lengths of pipe of different diameters may be advantageously employed to provide a seal or trap for the governor; and to provide certain details and features of construction and combinations tending to increase the general efficiency and serviceability of a fluid-pressure governor of this particular character.

To the foregoing and other useful ends, my invention consists in matters hereinafter set forth and claimed.

In the accompanying drawings:

Figure 1 is a longitudinal vertical section of a fluid-pressure governor embodying the principles of my invention.

Fig. 2 is a vertical section on line 2—2 in Fig. 1.

Fig. 3 is a vertical section on line 3—3 in Fig. 1.

Fig. 4 is a plan view of a portion of the governor, showing the cover thereof removed.

Fig. 5 is an enlarged horizontal section on line 5—5 in Fig. 1.

Fig. 6 is a plan of the governor shown in Fig. 1.

As thus illustrated, my invention comprises a casing A of the well-known form and construction, having a lower inlet B and an outlet C at one end thereof. The usual diaphragm D is disposed horizontally on the rim of the casing and is clamped in place by the removable cover d, which latter is secured in place by screws 1 in the usual and well-known manner. A spring 2 bears upon the top of said diaphragm, and the tension of this spring is regulated by the screw 3 in the top of the cover, thereby to adjust the tension of the diaphragm and regulate the action of the governor. The bottom of said diaphragm is provided with a bracket E which is removably held in place by the screw e inserted downwardly through the diaphragm. The lower end of this bracket is provided with a pivot 4 which may be a bolt or rivet, and which extends transversely through the lower fork-portion 5 of said bracket. The horizontally-disposed lever F is provided with a transverse pivot f which is supported in bearings 6 formed on the inside of the casing A (see Fig. 4), and the other end of this lever is provided with a longitudinal slot 7 for the pivot 4, whereby this lever when lifted from its pivot-bearings may be moved endwise until the pivot 4 reaches the other end of said slot. A screw-threaded-member G is screwed downwardly into a threaded socket g in the shorter end-portion of said lever, and is provided with an adjustable screw-threaded-support H provided at its lower end with a ball h, the upper end of this support having a slot or groove 8 for a screw-driver. The movable valve-element I is adapted to engage the stationary valve-seat i, being provided with a leather face 9 for this purpose, said valve-seat being the upper end of a screw-threaded plug, as shown, and being preferably formed with a thin edge which makes a circular indentation in the said leather. The top of this valve-element I is provided with a socket 10 for the ball h, so that a socket-joint is provided between the said valve-element and the said support, which permits the valve-element to rock around and adjust itself to the valve-seat. The threaded-member G has a vertical hole 11 at one side of the support H, and the valve-element I has a vertically-disposed pin 12 which extends upwardly into said hole, with a loose fit, whereby the said valve-element cannot rotate about a vertical axis, but is free to rock around and adjust

itself to the valve-seat. The member G has a shoulder 13 which engages the top of the lever F to limit the downward insertion of said member, and which serves to prevent 5 the movable valve-element from being taken out and then replaced in a different position—that is to say, the taking out and replacement of the valve-element will not result in its being displaced or turned about a 10 vertical axis, at least not to any great extent, as the tightening of the valve-member G until its shoulder 13 is against the top of the lever F will always bring the valve-element I into the final position with the pin 12 in 15 about the position shown. In this way, the valve-element I, after it has become fitted to the valve-seat, will always have the same fit, or substantially so, after being taken out and replaced.

20 The valve-mechanism is provided with a separate cover J which is removable independently of the cover d, so that access can be obtained to said mechanism without removing the cover d or the diaphragm. This cover J has an opening j through which access can be obtained to said mechanism, for the adjustment thereof, and this opening is normally closed by the plug 14 which is screwed therein, or by any other suitable means. This cover J is provided with depending lugs 15 which are notched to fit 25 over the pivot f, one at each side of the lever F, thereby holding the said lever against lateral displacement. With this construction, the bearings 6 do not need to be accurately finished or formed. The lugs 15 are finished on their inner surfaces, and where they engage the pivot f, but this is an easy operation inasmuch as the cover J 30 is a flat piece of metal which makes it convenient to handle. The bearings 6, however, are inside of the casing, and it would be somewhat difficult to accurately finish these bearings; but with the construction shown this is not necessary, inasmuch as the lugs 15 are depended upon to accurately 35 position the lever F and its pivot f and thereby insure accuracy in the operation of the valve-mechanism.

40 The gas enters at B and passes up through the casing and out through the opening C, it being understood that these internally-threaded-bosses are connected with gas pipes in any suitable manner. When the pressure becomes too great, the diaphragm D moves 45 upward and thereby causes the valve-element I to move downward against the valve-seat. As soon as the pressure in the governor is reduced, the valve is then automatically opened.

50 The interior of the casing below the diaphragm communicates with the upper end of a short section of relatively short pipe K which has its upper end screwed into the 55 bottom of the chamber of the casing. A

cavity L is formed below said chamber, around the upper portion of said pipe, and a short section of relatively large pipe M is screwed into the bottom of this cavity, being telescoped over the smaller pipe. The 70 two pipes are of suitable length, and the larger pipe is filled with a heavy oil or liquid which will form a seal or trap. The lower end of the pipe K does not come quite to the bottom of the pipe M, the lower end 75 of the latter being closed by a cap m or any other suitable means. An outlet l communicates with the cavity L, in the usual and well-known manner, to which a blow-off pipe can be secured. Thus, the pipe-sections K 80 and M are advantageously employed to form an effective seal or trap, and this is particularly advantageous when a heavy oil is to be used as a substitute for mercury, as in such case a greater depth is necessary.

85 The screen N in the intake serves to keep dirt, etc., from entering the governor. It will also be seen that the depending edge n which is the lower end of said screw-threaded plug forming the valve-seat will 90 extend to prevent particles of scale from entering the governor, as they will be prevented from sliding along and entering the hole. In other words, the particles of scale 95 will have a tendency to collect in the cavity or pocket extending around outside of this depending edge n, and will not enter the opening.

What I claim as my invention is:—

1. In a fluid-pressure governor, a pivoted 100 lever, devices to operate said lever, a valve-seat, a member screwed into said lever, a support screwed into said member, a movable valve-element to engage said valve-seat, a ball-and-socket joint between said support 105 and valve-element, and means to prevent rotation of said movable valve-element when said support is adjusted.

2. In a fluid-pressure governor, a pivoted 110 lever, devices to operate said lever, a valve-seat, a member screwed into said lever, a support screwed into said member, a movable valve-element to engage said valve-seat, a ball-and-socket joint between said support 115 and valve-element, and means to prevent rotation of said movable valve-element when said support is adjusted, said governor having a casing provided with an opening immediately over said member, so that said support may be adjusted, and removable 120 means to close said opening.

3. In a fluid-pressure governor, a pivoted 125 lever, devices to operate said lever, a valve-seat, a member screwed into said lever, a support screwed into said member, a movable valve-element to engage said valve-seat, a ball-and-socket joint between said support 130 and valve-element, and means to prevent rotation of said movable valve-element when said support is adjusted, said lever

135

having a threaded opening therein for said member and through which said valve-element may pass when said member is unscrewed therefrom.

- 5 4. In a fluid-pressure governor, a pivoted lever, devices to operate said lever, a valve-seat, a member screwed into said lever, a support screwed into said member, a movable valve-element to engage said valve-seat,
- 10 10 a ball-and-socket joint between said support and valve-element, and means to prevent rotation of said movable valve-element when said support is adjusted, said governor having a casing provided with a cover composed of separate and independently-removable sections, one of said cover-sections being disposed in position to afford access to said valve.
- 15 5. In a fluid-pressure governor, a lever, a pivot-bearing for said lever, a valve operated by said lever, and means to operate said lever, said pivot-bearing permitting raising of said lever therefrom, and said lever having a slot for engaging said means to permit endwise shifting of said lever when lifted from its pivot-bearing, thereby to afford access to the valve-seat.
- 20 25 6. In a fluid-pressure governor, a lever, a pivot-bearing for said lever, a cover having lugs to position said lever and obviate the necessity for accurate formation of said pivot-bearing, a valve operated by said lever, and means to operate said lever, said lugs being spaced apart to embrace the lever and notched to engage the pivot.
- 25 7. In a fluid-pressure governor, a lever, a pivot-bearing for said lever, a cover having lugs to position said lever and obviate the necessity for accurate formation of said pivot-bearing, a valve operated by said lever, and means to operate said lever.
- 30 8. In a fluid-pressure governor, a lever, a pivot-bearing for said lever, a cover having lugs to position said lever and obviate the necessity for accurate formation of said pivot-bearing, a valve operated by said lever, and means to operate said lever.

pivot-bearing for said lever, a valve operated by said lever, means to operate said lever, said pivot-bearing permitting raising of said lever therefrom, and said lever having a slot for engaging said means to permit endwise shifting of said lever when lifted from its pivot-bearing, thereby to afford access to the valve-seat, a cover, and means on said cover to position said lever and obviate the necessity for accurate formation of said pivot-bearing.

8. In a fluid-pressure governor, a lever, a pivot-bearing for said lever, a cover having lugs to position said lever and obviate the necessity for accurate formation of said pivot-bearing, a valve operated by said lever, and means to operate said lever, said lugs being spaced apart to embrace the lever and notched to engage the pivot.

9. In a fluid-pressure governor, a pivoted lever, devices to operate said lever, a valve-seat, a member screwed into said lever, a support screwed into said member, a movable valve-element to engage said valve-seat, a ball-and-socket joint between said support and valve-element, and means to prevent rotation of said movable valve-element when said support is adjusted, said means including an upright pin on said valve-element and a hole in said member to receive said pin loosely therein.

Signed by me at Chicago, Illinois, this 24th day of May, 1916.

ARTHUR L. SMYLY.
